(57) **CLAIM**

The ornamental design for a hinge strap as shown and described.

DESCRIPTION

FIG. 1 is a perspective view of a hinge strap showing our new design.

FIG. 2 is a front view thereof.

FIG. 3 is a rear view thereof.

FIG. 4 is a top view thereof.

FIG. 5 is a bottom view thereof.

FIG. 6 is a left side view thereof; and,

FIG. 7 is a right side view thereof.

The broken lines depict portions of the hinge strap indicate unclaimed portions and form no part of the claimed design.

1 Claim, 6 Drawing Sheets
